UNITED STATES PATENT OFFICE.

ELIJAH N. KING, OF HARGETT, KENTUCKY.

SWITCH-RAIL.

1,257,878.

Specification of Letters Patent. Patented Feb. 26, 1918.

Application filed April 14, 1917. Serial No. 162,109.

To all whom it may concern:

Be it known that I, ELIJAH N. KING, a citizen of the United States, residing at Hargett, in the county of Estill and State 5 of Kentucky, have invented new and useful Improvements in Switch-Rails, of which the following is a specification.

This invention relates to railway switches.

The primary object is to provide siding 10 rails which may be secured at any point in the main track rails for the purpose of providing a temporary switch or siding, it not being necessary to interfere in any way with the main track rails in the positioning 15 and use of the switch.

A further object of the invention is the provision of temporary siding rails which are so formed as to engage or fit the side 20 portions or fishing spaces of the main track rails in order to aid in holding in position the said siding rails.

A still further object is the provision of temporary siding rails which are provided with tapered ends overlying the heads of the main rails, so as to provide a gradual 25 elevation of the siding rails to permit their passage over the top of the main rails.

With the above and other objects in view the invention consists of the following novel 30 combination and arrangements of parts hereinafter more fully described, illustrated in the accompanying drawings and pointed out in the appended claim.

In the drawings:—

35 Figure 1 is a plan view of a main line track equipped with temporary siding rails constructed in accordance with the invention;

Fig. 2 is an enlarged cross sectional view 40 taken through one of the main track rails and the adjacent engaging end of the siding rail.

Fig. 3 is a detailed perspective view of 45 the tapered end of the siding rail; and

Fig. 4 is a detailed perspective view of the clamp.

The invention in its practical form comprises a pair of grooved siding rails 10, which are adapted to be temporarily secured 50 to the main track rails 11 by means of suitable clamping devices 12.

The siding rails are formed at their ends which engage the main track rails with an enlarged portion 13 the bottom of which is 55 adapted to lie flush with the base flanges of the main track rail. This enlarged end 13

is of substantially L-shape in cross section, that portion which engages the side of the main track rails being formed with a longitudinal rib 14, which is adapted to fit 60 snugly within the fishing spaces of the main track rails and to aid in holding the siding rails thereto by preventing upward movement. As illustrated in Fig. 3 the end of this portion of the siding rails is finely tapered so as not to present any obstruction 65 to the flanges of the car wheels. The top portions 15 of the siding rails is also tapered and is adapted to fit and overlie the head of the rails 11 as shown. This formation provides a groove 16 between the overlying portion 15 and the rib 14 of the siding rails, the grooves 16 snugly fitting the heads 70 of the main track rails. The overlying portions 15 as before stated are tapered in order 75 to provide a gradual elevation of the heads of the siding rails above the main track rails, this elevation enabling the laying of the siding rails over the said main track rails so as to render it unnecessary to interfere with 80 the main track rails.

For the purpose of securing the siding rails to the main track rails, there is employed the clamp 12, this clamp being formed with a notch 17, which includes the 85 oppositely located recesses 18 for engagement with the base flanges of the main line and siding rails. As the enlarged portion 13 of the siding rails is tapered, this clamp may be driven upon this tapered portion so 90 to securely hold the rails together.

It will be seen from the foregoing description when taken in connection with the accompanying drawings that the invention provides an economical and convenient 95 means for temporarily securing the siding switch at any point along the main line, the securing means holding the siding rails in position until their removal is desired. By constructing the siding in the manner shown 100 it is unnecessary to in any way interfere or tear up any portion of the main track rails, so that the siding may be removed and the main track remain in its former condition.

Having described the invention, what is 105 claimed, is:—

In a railway switch, the combination with main track rails, of siding rails each provided with tapered ends adapted to engage the main track rails, said tapered ends each 110 including longitudinal ribs adapted to fit within the fishing spaces of the main track

rails, a tapered flange adapted to overlie the head of one of the main rails, said flange and rib defining a groove to snugly fit the head of the main track rail, a flange overlying the uppermost surface of one side of the base of the rail, said last mentioned flange and portion of the side rail extending over the head of the main rail defining a longitudinal groove, a clamp surrounding

the lower portions of the main track rail 10 and the tapered end of the side rail and inwardly extending inclined ends carried by said clamp, one of said ends engaging the last mentioned longitudinal groove and the other end engaging the fishing space upon 15 the opposite side of the main track rail.

In testimony whereof I affix my signature.

ELIJAH N. KING.

Copies of this patent may be obtained for five cents each, by addressing the "Commissioner of Patents, Washington, D. C."
